(57) **CLAIM**

We claim the ornamental design for a tie, as shown and described.

DESCRIPTION

FIG. 1 is a front perspective view of a tie, showing our new design;

FIG. 2 is a front elevational view thereof;

FIG. 3 is a rear elevational view thereof;

FIG. 4 is a right-side elevational view thereof, the left-side elevational view being a mirror image thereof;

FIG. 5 is a top plan view thereof; and,

FIG. 6 is a bottom plan view thereof.

The broken lines in FIGS. 1 and 2 represent stitching, and form part of the claimed design.
